AUTOMATIC SEWING MACHINE

Irving F. Webb, Elizabeth, N. J., assignor to The Singer Manufacturing Company, Elizabeth, N. J., a corporation of New Jersey

Application June 30, 1934, Serial No. 733,226

9 Claims. (Cl. 112—2)

This invention relates to sewing machines and has for a particular object to provide a sewing machine for automatically and temporarily tacking together at spaced intervals superposed edge-portions of long lengths of fabric materials while in continuous motion past the sewing station.

Generally, the invention has for an object to provide a sewing machine for automatically and repeatedly performing disconnected group-stitching operations at spaced intervals lengthwise of fabric strip material while in continuous motion past the sewing station.

With the above and other objects in view, as will hereinafter appear, the invention comprises the devices, combinations, and arrangements of parts hereinafter set forth and illustrated in the accompanying drawings of a preferred embodiment of the invention, from which the several features of the invention and the advantages attained thereby will be readily understood by those skilled in the art.

In the accompanying drawings, Fig. 1 is a side elevation, partly in section, of a sewing machine embodying the invention. Fig. 2 is a top plan view of the machine. Fig. 3 is a front elevation, partly in section, of the machine. Fig. 4 is a section on the line 4—4, Fig. 3. Fig. 5 is a section on the line 5—5, Fig. 1. Fig. 6 is a section on the line 6—6, Fig. 1, and Figs. 7 and 8 are fragmentary elevational views of the automatic work-clamp-opening and closing mechanism of the machine.

1 represents the top of a supporting bench or table on which the machine is stationed for use. Extending downwardly through a hole 2 in the table-top 1 is a supporting frame in the form of a tapered cylindrical housing 3 the supporting flange 4 at the upper end of which is screwed fast to the table-top. Journaled in ball-bearings 5 in the housing 3 is the vertical shaft 6 to the upper end of which is fixed the turntable casting 7 upon which is mounted a conventional sewing machine head A, such as the well known Singer 114-31 class machine adapted, when started, to automatically sew a group of a predetermined number of single-chain tacking stitches and then come to rest.

A sewing machine head A of the class in question commonly has a frame including a bed 8, and standard 9 of an overhanging bracket-arm 10 terminating in a head 11 in which is mounted the vertically reciprocating needle-bar 12 carrying the needle 13. The needle-bar 12 is driven as usual by the main-shaft 14 which also drives the rotary chain-stitch looper 15 with which the needle 13 cooperates in the formation of stitches.

The machine has a spring-closed work-clamp including a lower main supporting bar 15 slidable longitudinally of the bed 8 and carrying a lower work-clamping plate 16. The work-clamp further comprises an upper pivoted clamping bar 17 pressed downwardly by the usual leaf-spring 17' and carrying a work-clamping foot 18, having a hole 19 in it through which the needle 13 works in sewing a group of stitches. During the sewing operation the work-clamp is reciprocated longitudinally of the bed 8 by the usual connections with the pattern cam 20 which is slowly driven by the main-shaft 14 through the worm-and-gear connection 21.

The period of operation of the sewing machine 15 head is controlled by the usual start- and stop-motion device including the tight and loose belt-pulleys 22, 23 and the stop-cam 24 on the shaft 14, with which cooperates the tilting stop-motion lever 25 fulcrumed at 26 and carrying the belt-shipper 27. A starting lever 28 is fulcrumed at 29 on the frame of the sewing machine head A and has a nose 30 which shifts the stop-motion lever 25 to starting position when the starting rod 31 connected to the lever 28 is pulled downwardly. It will be understood that the stop-motion lever 25 is latched as usual in running position and is automatically tripped to stop the machine at the completion of a sewing period by the usual tripping point (not shown) on the pattern cam 20. A stop-motion device of this construction is well known and shown, for example, in the United States patents to Barron, No. 1,093,241, of Apr. 14, 1914, and Fifield, No. 1,498,649, of June 24, 1924, which latter embodies a braking device represented in the drawings of the present application by the reference number 32.

The work-clamping foot 18 is lifted clear of the work by means of the clamp-lifting lever 33 which is fulcrumed at 34 on the bracket-arm 10 and at its forward end is connected to the vertical slide-rod 35 carrying at its lower end a bracket 36 underhanging the upper horizontal end of the post 37 on the upper clamp-arm 17, as disclosed in the patent to Gatchell, No. 1,036,603, of Aug. 27, 1912. A down-pull on the rod 38 connected to the lever 33 lifts the clamp-foot 18 to release the work and, when the down-pull is relieved, the clamp-foot is pressed downwardly to closed position by the usual leaf-spring 17' referred to.

The machine is also equipped with the usual automatic thread-cutter t, of U. S. Patent No. 1,251,451, of Dec. 25, 1917, which severs the sewing

55

thread below the work at the completion of a sewing period.

The turntable 7 has a rearward extension 7' from which the downward extension 39 depends 5 through the arcuate hole or slot 38' in the tabletop. Bolted to the downward extension 39 of the turntable 1 is the driving motor 49 the power-shaft 41 of which carries a belt-pulley 42 connected by the belt 43 to the tight and loose 10 pulleys 22, 23, respectively, of the sewing machine head A. The power-shaft 41 of the motor also carries a belt-pulley 44 connected by a belt 45 to a pulley 46 on the worm-shaft 47 journaled in a fixture or bracket 48 fast on the lower end of 15 the turntable shaft 6. The worm-shaft 47 carries a worm 49 meshing with a slow running gear 50 journaled on the stud-pin 51 carried by the fixture or bracket 43. The gear 50 is formed on its upper face with a radially slotted and undercut block 52 to receive and support the radially 20 adjustable crank-pin 53 carrying at its upper end a crank-bearing block 54 working in a guideway 55 in an arm 56 screwed to the supporting frame or housing 3. By the mechanism described, a comparatively slow oscillatory motion 25 is imparted to the turntable 7 and sewing machine head A. The amplitude of this oscillatory motion may be varied by adjustment of the crank-pin 53 radially of the gear 50. In the 30 present instance the machine is oscillated through the angle between the lines a and f, Fig. 2, which is about 40°. The motor 49 is connected by the brace 48' to the lower end of the turntable shaft 6.

35 The superposed plies of material B to be tacked together at intervals are reeled continuously at a uniform speed in a horizontal plane at the level of the space between the work-clamping elements 16, 18 by any suitable reeling mechanism. The oscillating sewing machine head A is so controlled that in its oscillatory movement 40 in the direction of the arrow, Fig. 2, the work-clamp is closed at the position b; the stitch-forming mechanism is started at the position c and stopped at the position d, following which 45 the work-clamp is opened at the position e.

The time required by the work-clamping foot 18 to travel the distance from the position b to the position e is approximately equal to the time 50 required by the continuously moving fabrics B to travel the same distance. Any momentary differences between the fabric speed and the speed of lateral movement of the closed work-clamp are inconsequential, as the fabric will stretch 55 enough momentarily to accommodate such differences. The group of tacking stitches C is repeated indefinitely at regular intervals lengthwise of the material being reeled.

The clamp opening and closing mechanism 60 is shown in Figs. 7 and 8. Mounted on the turntable 7 is a bracket 57 in which is journaled a rock-shaft 58 to which is fixed a crank-arm 59 connected to the lower end of the clamp-opening pull-rod 38. There is also fixed to the rock-shaft 58 a depending arm 60 carrying the roller-stud 61. A third arm 62 fixed to the rock-shaft 58 is adapted to be engaged at times by the spring-influenced latch 63 pivotally carried by the bracket 57 to hold the clamp-foot 18 in elevated or open position.

When the sewing machine reaches the position b, Fig. 2, the pin 64 on the latch 63, Fig. 7, encounters the spring-influenced tripping arm 65 fulcrumed at 66 on a bracket 67 carried by the 75 table 1 and braced by the stop-pin 65' and shifts

the latch 63 to release the arm 62, whereupon the down-pull on the rod 38 is relieved and the work-clamp springs shut or closes upon the work.

When the position e is approached, the roller-stud 61, Fig. 8, encounters the pivoted and spring-influenced arm 68 carried by the table-bracket 69 and braced in one direction by the stop-pin 68' and temporarily arrests movement of the roller-stud. The continued movement of the bracket 57 and turntable 7 in the direction of 10 the arrow, Fig. 8, rocks the shaft 58 to open the work-clamp which is held open by the engagement of the arm 62 by the spring-influenced latch 63. In the return oscillation of the parts, the roller-stud 61 wips idly by the pivoted arm 15 68 which is free to yield away from its stop-pin 68'. Similarly, the pin 64 on the latch 63 wips idly by the trip-arm 65.

The stitch-forming mechanism is started at the position c, Fig. 2, by means of a fixed stud 20 70, Figs. 1 and 5, adjustable horizontally in the slot 71 in the supporting bracket 72 screwed to the table-top 1. This stud is engaged by the roller-stud 73 on the crank-arm 74 fixed to the rock-shaft 75 journaled in the turntable extension 39. The rock-shaft 75 carries a crank-arm 76 which is connected to the starting pull-rod 31.

After the sewing mechanism is started at the position c, it runs until the position d is reached at which position the normal sewing period of 30 the machine is completed and the machine automatically comes to rest with the stitching thread severed.

The invention is not to be understood as limited to the details of construction and relative 35 arrangements of parts shown and described, as various modifications will be apparent to those skilled in the art within the spirit and scope of the invention.

Having thus set forth the nature of the invention, what I claim herein is:—

1. The combination with a sewing machine head adapted when started to automatically sew a group of stitches and then come to rest, said sewing machine head having stitch-forming 45 mechanism, a start- and stop-motion device, and a work-clamp, of a motor connected to drive said sewing machine-head, an oscillatory sewing machine support driven by said motor for repeatedly moving said sewing machine head alternately in opposite directions, and control devices actuated automatically during the movement of said machine head in one direction to close the work-clamp, start the stitch-forming mechanism and finally open the work-clamp at the completion 55 of a group of stitches.

2. The combination with a sewing machine head adapted when started to automatically sew a group of stitches and then come to rest, said sewing machine head having stitch-forming 60 mechanism, a start- and stop-motion device, and a work-clamp, of a motor connected to drive said sewing machine head, an oscillatory turntable driven by said motor and carrying the sewing machine head, and control devices actuated 65 by the oscillatory movement of said turntable in one direction for closing the work-clamp, starting the stitch-forming mechanism and finally opening the work-clamp at the completion of a group of stitches.

3. In combination, a turntable shaft, a turntable fixed to said shaft and having a rearward extension, a cylinder-bed sewing machine of the automatic group-stitching type mounted on said turntable with its bed extending forwardly away 75

- from said extension, a motor mounted on said extension and connected to drive said sewing machine, said motor substantially balancing the sewing machine relative to said turntable shaft, 5 and means for oscillating said shaft.
4. In combination, a turntable shaft, a turntable fixed to said shaft and having a rearward extension, a cylinder-bed sewing machine of the automatic group-stitching type mounted on said 10 turntable with its bed extending forwardly away from said extension, a motor mounted on said extension and connected to drive said sewing machine, said motor substantially balancing the sewing machine relative to said turntable shaft,
- 15 means for oscillating said shaft, and control devices actuated by the oscillatory movement of said turntable in one direction for starting said sewing machine.
5. In combination, a sewing machine of the 20 type adapted, when started, to sew a group of stitches and then come to rest, said machine having a stitch-forming mechanism, a stop-motion device, and a work-clamp, a motor for driving said sewing machine, means driven by said motor for oscillating said sewing machine and motor about a vertical axis, and spaced devices relative to which said machine oscillates for both closing and opening the work-clamp in an oscillatory movement of said machine in one direction.
- 25 6. The combination with a turntable shaft, of a supporting frame in which said shaft is journaled, said frame including an arm having a guideway transverse to said shaft, a bracket fixed to said shaft, a crank-member journaled on said bracket and engaging said guideway, a turntable carried by said shaft, a sewing machine and driving motor carried by said turntable, and means
- connected to said motor for driving said crank-member at a slow speed.
7. The combination with a turntable shaft, of a tubular housing in which said shaft is journaled, said housing having a supporting flange 5 at its upper end, whereby it may be suspended through a hole in a table, a turntable mounted on the upper end of said shaft, a sewing machine and driving motor mounted on said turntable, and means driven by said motor and connected 10 to the lower end of said shaft for oscillating the latter.
8. In combination, a sewing machine having a spring-closed work-clamp, an oscillatory support for said sewing machine, a table carrying said 15 oscillatory support, means for opening said work-clamp, a latch for holding said work-clamp open, and means on said table for tripping said latch, said last mentioned means and the means for opening the work-clamp being automatically operated one after the other by the oscillatory movement of the sewing machine supporting means in one direction relative to said table.
9. In combination, a support, a turntable shaft journaled in said support, a turntable fixed to 25 the upper end of said shaft, a motor depending from said turntable, a bracket fast to the lower end of the turntable shaft, a worm shaft journaled in said bracket and connected to be driven by said motor, a gear driven by said worm shaft 30 and journaled on said bracket, a crank carried by said gear, an arm carried by said support and having a guideway engaged by said crank, and a sewing machine carried by said turntable and connected to be driven by said motor. 35

IRVING F. WEBB.
